Primary Examiner — Cathy A MacCormac*(74) Attorney, Agent, or Firm* — Boyle Fredrickson, S.C.(57) **CLAIM**

The ornamental design for a catnip toy, as shown and described.

DESCRIPTION

FIG. 1 is a front view of a catnip toy incorporating my new design, with the rear view mirror being a mirror image of the front view.

FIG. 2 is a top plan view thereof, the bottom plan view being a mirror image thereof; and,

FIG. 3 is a right side elevation view thereof, with the left view being a mirror image of the right side.
